(57) **CLAIM**

The ornamental design for a drug container holder, as shown and described.

DESCRIPTION

FIG. 1 is a top, side and distal end perspective view of a drug container holder showing our new design;

FIG. 2 is a distal end view;

FIG. 3 is a proximal end view;

FIG. 4 is a side elevation view having an opposite side being a mirror image; and,

FIG. 5 is a top plan view having a bottom side being a mirror image.

1 Claim, 4 Drawing Sheets
